UNITED STATES PATENT OFFICE.

NATHAN L. HOLMES, OF RACINE, WISCONSIN.

WAGON-GEAR.

SPECIFICATION forming part of Letters Patent No. 380,893, dated April 10, 1888.

Application filed July 30, 1887. Serial No. 245,664. (No model.)

To all whom it may concern:

Be it known that I, NATHAN L. HOLMES, of Racine, in the county of Racine and State of Wisconsin, have invented certain new and useful Improvements in Wagon-Gears; and I do hereby declare that the following is a full, clear, and exact description thereof, reference being had to the accompanying drawings, and to the letters of reference marked thereon, which form a part of this specification.

This invention relates to an improved means in the nature of flanged metal castings or coupling-pieces for connecting the rear ends of the front axle-hounds with the sway-bar of a wagon-gear.

The invention consists in the matters hereinafter described, and pointed out in the appended claims.

The improved device herein shown as embodying my invention embraces as its main features of construction two flanged castings adapted to fit over and embrace the upper and lower surfaces and the sides of the adjacent ends of the wooden hounds and sway-bar.

Each of said castings is provided upon the inner surface of its horizontal wall with an inwardly-projecting part adapted to fit a shallow transverse notch or gain in the adjacent top or bottom surface of the hound or sway-bar, whereby the said hounds and sway-bar are positively held from being withdrawn from engagement with the castings. The said castings are connected with each other by bolts passing through them and through the ends of the hounds and sway-bar, as hereinafter fully set forth.

The invention may be more fully understood by reference to the accompanying drawings, in which—

Figure 1 is a plan view of the hounds and sway-bar provided with connecting devices constructed in accordance with my invention. Fig. 2 is a side view of the same. Fig. 3 is a sectional elevation of the joint between the hounds and sway-bar, taken upon line 3 3 of Fig. 1. Fig. 4 is a sectional view taken upon line 4 4 of Fig. 1. Fig. 5 is an enlarged detail section taken upon line 5 5 of Fig. 1. Fig. 6 is a perspective view of the two parts or castings of the device separated from each other. Fig. 7 is an enlarged transverse sec-

tion through the said castings, taken upon line 7 7 of Fig. 1.

As shown in the said drawings, A A indicate the axle-hounds and B the sway-bar. 55 C C' indicate a pair of castings or coupling-plates affording means for connecting the ends of the sway-bar with the hounds.

D is a metal bar or strap attached to the upper surface of the sway-bar to prevent the latter from being worn by contact with the reach.

E E are the circle-posts attached to the upper surface of the hounds, E the circle, and F F the braces which extend from the outer portion of the hounds to the under side of the 65 axle G.

H H' H² H³ are bolts inserted through the hounds and sway-bar and the said castings for holding the said parts together, and H⁴ H⁴ are bolts employed for securing the strap D to the 70 sway-bar.

The casting C consists, mainly, of a flat plate, which is placed over the top surfaces of the adjacent parts of the hounds and sway-bar, and is provided at its side margins with two 75 deep flanges, c c, which extend over the adjacent side portions of the said hounds and sway-bar. The casting C' similarly covers the under surface of the adjacent end portions of the hounds and sway-bar, and is provided with 80 deep flanges c' c', which extend over the surfaces of the said hounds and sway-bar and meet or nearly meet the similar flanges, c c, of the casting C. The said casting C is further provided upon its inner surface, at its end which 85 engages the sway-bar, with a projection, C³, extending across the inner surface of the plate between the flanges c c, and adapted to enter and fit closely within a transverse notch or gain, b, cut in the top surface of the sway-bar, 90 Figs. 3 and 5, while the casting C' is similarly provided at its end which engages the hound with an inwardly-projecting part, C⁶, extending across the inner surface of the plate between the flanges c' c', and adapted to fit closely 95 within a transverse depression or gain, a, cut in the end portion of the hound, in the manner clearly shown in Figs. 4 and 6. This construction obviously affords interlocking parts upon the connected castings C and C' and the 100 sway-bar and hounds, whereby the wooden parts are positively held from being drawn

endwise out of engagement with the said castings, notwithstanding, the loosening of the parts by shrinkage of the wood or from other causes.

5 In the upper surface of the casting C and in the lower surface of the casting C', exterior to the transverse projections C³ and C⁶, are formed depressions or recesses C⁴ C⁷, said recesses being adjacent to the end faces of the horizontal parts or plates of said castings and being extended into the said plate from the end thereof a distance somewhat less than the horizontal thickness of the said projections C³ C⁶. In other words, the horizontal walls or plates of the castings are set in or offset adjacent to the ends of the castings, so that the projections C³ C⁶ and the recesses C⁴ C⁷ are formed without making the casting any thicker adjacent thereto than at other points, as clearly seen in Figs. 4 and 5. The recess C⁷ of the top casting, C, is constructed to receive the end of the strap D, which is secured to the top surface of the sway-bar in such manner as to allow the latter to come flush with the adjacent upper surface of the casting, said recess C⁷ for this purpose preferably being made of the same depth as the thickness of the said strap. The recess C⁴ of the casting C' is similarly constructed to receive the end of the inclined brace F, by which the outer end of the hound is connected with the lower surface of the axle. One of the bolts H', by which the castings are secured to each other and to the hounds and sway-bar, is preferably inserted through the end portion of the strap D and through a bolt-hole, c², formed through the wall of the casting in the said recess C⁴, and another bolt H' is similarly inserted through the end of the brace F and a hole, c³, located within the recess C⁷ of the casting C'. The placing of the bolts through the said brace and strap and through the bolt-holes of the castings obviously serves to rigidly connect the several metal parts to each other, thereby adding greatly to the durability and strength of the structure. The employment of the recess C⁴ for the end of the strap D is, furthermore, of great advantage, for the reason that it insures the support of the end of the strap flush with the casting C, so that the upper surface of the sway-bar, over which the reach slides or moves, is rendered perfectly smooth, it being entirely obvious that if the said casting C and the strap were separate from each other and connected solely by the wooden part of the sway-bar any irregularity in the surface of or warping or shrinkage of the sway-bar would change the position of the strap with relation to the casting, and thus throw the upper or bearing surfaces of the said parts out of the same plane, and thus produce irregularity or roughness in the bearing-surface against which the reach acts. Another advantage gained by the presence of the said recess C⁷ is that, when the end of the strap is placed therein and the bolt inserted through the end of the strap and the part of the cast-

ing beneath it in the manner described, said bolt may be tightened to any desired extent in clamping the parts together without affecting 70 the relative position of the end of the strap and said casting.

At the end of the casting C opposite the recess C³, and adjacent to the hound, the main part or horizontal plate forming the body of 75 said casting is prolonged to form an arm, C², which extends over the upper surface of the hound toward the axle, and is secured to the hound by bolts H² H³. The said arm C² in the particular construction herein shown extends 80 to the adjacent circle-post E of the hound, and is constructed to afford a support for the latter. The said circle-post, when this construction is employed, may be conveniently secured in place upon the hound by means of a long bolt, 85 H³, which extends through the circle-post and the extremity of the arm C² and through the hound. As illustrated in Fig. 4, the brace F, the end of which is secured in the recess C⁷ of the lower casting, C', in the manner above described, is extended along the under surface of the hound, and is also secured thereto by the bolts H² and H³. The lower casting, C', is also desirably provided with an arm or projection, C⁵, extending beneath the sway-bar 90 and secured to the latter by one of the bolts, H⁴, by which the strap D is secured in place upon the sway-bar.

The employment of the arms C² and C⁵ upon 100 the castings C and C' is of great advantage, inasmuch as said arms form points of attachment to the hounds and sway-bar at considerable distances from the ends of said parts, thereby adding greatly to the strength and rigidity of the connection between them.

105 As a further improvement in the coupling pieces or castings C, provided with arms C² or C⁵, in the manner described, the main horizontal parts of said castings, together with said arms, are made somewhat thicker than the side parts or flanges, and are recessed upon their under surfaces, so as to leave marginal ribs c⁴ c⁵ extending along the sides of the arms and along the edges of the castings adjacent to the flanges C and C', and preferably, also, around the bolt-holes. This construction affords a considerable degree of rigidity in the said arms without an undue increase in weight thereof, while at the same time it affords relatively small or narrow bearing-surfaces in 110 contact with the top and bottom surfaces of the wooden hounds and sway-bar. The advantage of this construction is that it enables me to force the metal slightly into the wood by the pressure of the bolts in bringing the 115 parts together, so that the castings may have a firm and solid bearing upon the wood throughout their entire length, not only when the parts are first put together, but after a considerable degree of shrinkage in the wood has occurred.

120 For the purpose of giving additional rigidity to the flanges c c' c' c' of said castings C C', vertical transverse flanges c⁶ c⁶ c' c' are formed at 125 the middle part of the said castings in such po-

sition as to come between the ends of the hounds and sway-bar, as clearly shown in Figs. 1, 6, and 7. The bolt H herein shown is located in the same plane with the said flanges $c^e c^f$, so that it is located between the ends of the hound and sway-bar, and serves only to connect the castings with each other.

For the purpose of giving a smooth bearing-surface at the top surface of the hounds and sway-bar in their parts between the circle-posts E E, the several bolt-apertures of the strap D and of the casting C are countersunk, and the heads of the bolts made flush with the top surfaces of the said strap and castings, in 15 the manner clearly shown in the drawings.

The castings or coupling-pieces made in the manner shown may be employed in connection with hounds and sway-bar made of any desired cross-sectional shape. In the particular construction shown, however, said hounds and sway-bar are rounded at their edges, and the flanges $c^e c^f c^g c^h$ are made flaring and concave upon their inner surfaces to fit the curvature of the said hounds and sway-bar. The flanged castings are preferably made slightly smaller in size than will easily fit over the ends of the hounds and sway-bar, and said castings are brought to place by the application of considerable pressure, thereby insuring a tight fit of 25 the parts, even when a considerable shrinkage of the wood afterward occurs.

A main feature of novelty in my invention is embraced in the construction in which the two flanged castings embracing the adjacent 35 end portions of the hounds and sway-bar are provided with transverse projections extending between the flanges and engaging transverse gains or notches formed in the upper and lower surfaces of the said hounds and 40 sway-bar, and this construction is herein broadly claimed, without restriction to any of the other details of construction illustrated and described. Other features of construction in the device illustrated are, however, also 45 novel, and are herein specifically claimed as part of my invention.

I claim as my invention—

1. The combination, with the hounds and sway-bar provided with transverse notches or 50 gains in their top and bottom surfaces, of coupling pieces or castings C and C', consisting of plates fitted against the top and bottom surfaces of the hounds and sway-bar and provided with marginal flanges embracing the 55 sides of said hounds and sway-bar, and with transverse projections upon the under sides of the said flat plates, said projections being constructed to engage the said notches or gains in the hounds and sway-bar, and clamping-bolts 60 inserted through the castings and the hounds and sway-bar for holding said parts together, substantially as described.

2. A metal coupling piece or casting, as C or C', connecting the hounds and sway-bar of 65 a wagon-gear, said coupling piece or casting consisting of a plate provided with marginal flanges and a transverse projection, as C^g or

C^h, on its inner surface adjacent to its end, and with an external recess, as C⁴ or C⁵, forming with the said projection an offset in the said 70 plate, said external recess being adapted to receive the end of a strap or brace attached to the hound or sway-bar, substantially as described.

3. The combination, with the hounds, a 75 sway-bar provided with a transverse notch or gain in its top surface near its end, and a strap, D, secured to the top surface of the sway-bar, of coupling pieces or castings C and C', consisting of plates provided with marginal flanges embracing the sides of the hounds and sway-bar, the said casting C being provided at one end with a transverse projection, C³, entering the said notch or gain in the sway-bar, and with an external recess, C⁴, constructed 80 to receive the end of the strap D, substantially 85 as described.

4. The combination, with a hound and sway-bar provided with notches *a* and *b* in their upper and lower horizontal surfaces adjacent 90 to their ends, of flanged castings C C', fitted over the end portions of the hound and sway-bar and provided with transverse inwardly-extending parts C³ C⁴, engaged with the said gains or notches *a* and *b*, and bolts inserted through 95 the said castings and the hound and sway-bar for holding the parts together, substantially as described.

5. The combination, with the hounds and sway-bar provided with transverse notches or 100 gains *a* and *b* in their top and bottom surfaces adjacent to their ends, of coupling pieces or castings C and C', consisting of plates fitted against the top and bottom surfaces of the hounds and sway-bar and provided with marginal flanges embracing the sides of said hounds and sway-bar, each of said castings C and C' being provided at one end upon its inner surface with a transverse projection engaging one of the notches or gains *a* and *b*, and with an 105 external depression or recess occupying the spaces external to the said projection, a metal strap, D, secured to the top surface of the sway-bar and having its end inserted in the recess of the casting C, a metal brace, E, having its end inserted in the recess of the casting C', and bolts inserted through said castings, strap, brace, hound, and sway-bar for securing said parts together, substantially as 110 described.

6. A coupling piece or casting, C or C', for connecting the ends of a hound and sway-bar, said coupling piece or casting consisting of a plate provided with marginal flanges embracing the sides of said hound and sway-bar and 115 prolonged to form an arm extending along the top or bottom surface of the hound or sway-bar, the under or inner surface of said plate and arm being recessed to form ribs which bear against the wooden hounds and sway-bar, substantially as described.

7. The combination, with hounds, sway-bar, and circle-posts of a wagon-gear, of means for connecting the hounds with the sway-bar, con-

sisting of two flanged coupling pieces or castings, C and C', embracing the top and bottom surfaces and the sides of said hounds and sway-bar in their parts adjacent to their ends, the castings C C' at the top of the hounds and sway-bar being provided with rigid extensions or arms C² C'², extending to a point beneath and supporting the said circle-posts, substantially as described.

In testimony that I claim the foregoing as my invention I affix my signature in presence of two witnesses.

NATHAN L. HOLMES.
